(57) CLAIM

The ornamental design for a caddy for a disposable head toilet cleaning system as shown and described.

DESCRIPTION

FIG. 1 is a perspective view of a caddy for a disposable head toilet cleaning system showing the new design for a caddy for a disposable head toilet cleaning system;

FIG. 2 is a left view thereof;

FIG. 3 is a right view thereof;

FIG. 4 is a rear view thereof;

FIG. 5 is a front view thereof;

FIG. 6 is a top view thereof; and,

FIG. 7 is a bottom view thereof.

The broken lines depict portions of the caddy for disposable head toilet cleaning system that form no part of the claimed design, and the shading is provided to illustrate contour only and is not an indication of texture, gloss, etc.

1 Claim, 6 Drawing Sheets
